UNITED STATES PATENT OFFICE.

JOHN BEHRINGER, OF CHICAGO, ILLINOIS.

NON-REFILLABLE BOTTLE.

1,080,318.

Specification of Letters Patent.

Patented Dec. 2, 1913.

Application filed December 19, 1912. Serial No. 737,681.

To all whom it may concern:

Be it known that I, JOHN BEHRINGER, a citizen of the United States, and a resident of the city of Chicago, county of Cook, and

5 State of Illinois, have invented certain new and useful Improvements in Non-Refillable Bottles, of which the following is a specification.

10 My invention relates to non-refillable bottles and particularly to the class which has a gravity actuated valve adapted to be closed when the bottle is in upright position.

15 The object of this improvement is to provide a simple and efficient bottle of this character.

Further objects will appear hereinafter.

The invention consists in the combinations and arrangements of parts hereinafter described and claimed.

20 The invention will be best understood by reference to the accompanying drawing forming a part of this specification, and in which,

25 Figure 1 is a vertical section of a bottle neck embodying my invention, Fig. 2 is a similar view but taken at approximately ninety degrees in a horizontal plane from the view shown in Fig. 1, Fig. 3 is a section taken on the line 3—3 in Fig. 1, Fig. 4 is a 30 section taken on the line 4—4 in Fig. 1, and Fig. 5 is an elevation of the upper portion of the plug employed in the construction.

35 The preferred form of construction, as illustrated in the drawing comprises a bottle neck 6 having shoulders 7 in its lower portion and longitudinally extending grooves 8. Said neck is also provided with laterally extending recesses 9 in an intermediate position. A lower portion 10 of a plug is positioned in the lower portion of the neck of the bottle with its bottom portion engaging the shoulder 7. The portion 10 is provided with a central opening 11 and a plurality of foot members 10' extending downwardly below the shoulder 7 forming recesses therebetween. In the upper portion of the member 10 is a valve seat 12 into which seats a valve 13. Said valve 13 is provided with a stem 14 extending through 40 the member 10 and provided with a weight 15 on its lower end. When the bottle is in inverted position, the weight 15 rests against the foot members 10' of the portion 10 there-

by permitting the flow of liquid through the recesses between said foot members into the 55 central passage 11 and through the valve seat 12.

An upper plug member 16 is provided with legs 17 which rest on the top portion of member 10. Said member 16 is provided 60 with ribs 18 which engage the grooves 8 of the bottle neck to prevent rotation of the member 16 in said bottle neck. The member 16 is provided with recesses around the lower portion of its outer side to allow liquid to 65 pass between the foot members 17 around the partition 19 thereof and perforations 20 are formed in the partition 19 to permit of a communication with the upper chamber 21 of the member 16, thereby allowing the liquid 70 to pass out of the bottle. A cork 22 may be provided in the upper portion of the neck 6 above the member 16 when so desired.

A spring actuated lock having two locking members 23 is mounted in a perforation 24 75 in the member 16 to lock the members 10 and 16 in the bottle neck when once inserted and will, as clearly shown, be securely locked against removal therefrom.

In operation the bottle is filled in the usual 80 manner and member 10 inserted in the neck 6 against the shoulder 7 and the member 16 inserted in the bottle neck and passed to its position, indicated, where the locks 23 will engage the recesses 9 to lock said members 85 therein. The bottle may be sealed in the usual manner with the cork 22. To empty the bottle, the cork 22 is removed, and the bottle inverted to permit the unseating of valve 13 which permits the liquid to flow 90 from the bottle. The perforations 19 are formed radially with relation to the member 16 so that it would be impossible to effect unseating of the valve 13 by means of a wire or like object thus preventing refilling the 95 bottle.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the 100 105 appended claim.

Having described my invention what I claim as new and desire to secure by Letters Patent is:

In a non-refillable bottle, the combination of a bottle neck; a two-part plug in said bottle neck, the lower of said parts having a valve seat in its upper face and the upper part having a laterally disposed central partition spaced concentrically from the bottle neck by ribs which extend downwardly and rest on said lower part, an outwardly flaring wall extending upwardly from said central partition with its top portion engaging the

bottle neck and having perforations establishing communication between the interior 15 of said flaring wall, through said perforations, around said central partition and to the valve seat in the lower part; and a valve in said valve seat, substantially as described.

In testimony whereof I have signed my 20 name to this specification in the presence of two subscribing witnesses.

JOHN BEHRINGER.
